FIG-2

FIG-3

FIG-1

FIGURE 1 is a perspective view of a combined litter and accessory container for automobiles, showing my new design;

FIGURE 2 is a top plan view thereof; and
FIGURE 3 is a rear elevation.

The side of the container which is not shown in FIGURE 1 is identical to the illustrated side, except that the design comprising the three vertical bars is disposed beneath the upwardly-extending ear which is provided adjacent the largest chamber. Thus, each three-bar design is identical to each other three-bar design, there being only one such design adjacent each corner of the unit. The bottom of the container is plain.

This application is a continuation-in-part of my earlier filed co-pending application Serial No. D78,991, filed March 13, 1964, and now abandoned.

I claim:

The ornamental design for a combined litter and accessory container for automobiles, substantially as shown and described.
